HENRY D. KLOTS, OF NEW YORK, N. Y.

MOUNT FOR SPINNING-SPINDLES.

SPECIFICATION forming part of Letters Patent No. 498,980, dated June 6, 1893.

Application filed January 14, 1893. Serial No. 458,819. (No model.)

To all whom it may concern:

Be it known that I, HENRY D. KLOTS, a citizen of the United States, residing in the city, county, and State of New York, have invented 5 a certain new and useful Improvement in Mounts for Spinning-Spindles, of which the following is a specification.

The general object of my invention is to provide for greatly reducing the diameter of 10 the bearing portion of the blades of spinning spindles, and thereby correspondingly increasing their practicable speed, with a proportionate gain in economy. The bearing portion of the spindle-blade in common use is 15 about three-eighths of an inch in diameter, and its limit of speed about twelve thousand turns a minute. If its diameter is greatly decreased for the purpose of allowing a higher speed, the blade will be bent by the lateral 20 stress to which it is subjected each time that the bobbin is doffed, and becomes permanently flexed, so that it will bind in its bearing with the result of greatly increasing the work required to drive it and lessening its 25 durability. This is due to the fact that in the prevailing form of spindle-mount, the spindle-blade is supported only at its bolster-bearing and its step-bearing, leaving the blade free to be bowed therebetween in yielding to 30 the flexure above the bolster-bearing. Further the sleeve-whirl does not prevent this flexure, for the reason that it is fixed to the spindle-blade so close to the center of flexure, which is immediately above the bolster-bearing, as to join only partially in the flexure of 35 the blade, and thus does not bear against the bearing-tube and support the blade until after the blade is flexed. The immediate aim of my invention is therefore to so improve the 40 mount of the spindle that the required reduction in diameter of the blade can be made without increasing its liability to flexure in "doffing." I attain this end by providing one normally inert bearing a considerable distance above, and, preferably, another below 45 and equally distant therewith from the upper end of the bolster-bearing, to be normally just out of contact with a part of the spindle, as the sleeve-whirl, but to bear against the same 50 and support the spindle-blade as soon as it is subjected to lateral stress, as in doffing the bobbin.

In order that my invention may be fully ascertained, I shall first describe in detail the mode in which I practice the invention and 55 then point out its distinctive features in the claim.

Reference is to be had to the accompanying drawings, forming part of this specification, in which—

Figure 1 represents a sectional elevation of 60 a spinning-spindle mount embodying my invention. Fig. 2 is sectional plan view of the same on the line 2 2 Fig. 1. Fig. 3 is a sectional plan view on the line 3 3, Fig. 1.

Like letters of reference designate corresponding parts in the several figures.

A designates the spindle-rail and B a self-adjusting universal-center bolster and step-bearing tube mounted thereon, substantially 70 as shown in Fig. 8 of and claimed in my Letters Patent No. 493,034, granted March 7, 1893, save that the bearing-sustaining springs C, in this instance, press against a collar D loosely surrounding the tube B. The method of supporting the bearing tube, however, whether rigidly or flexibly, does not concern my present invention. The diameter of the bearing portion E' of the blade E² of the spindle E herein shown is assumed to be reduced to one-third of that of the blade in common use, that is, to about one-eighth of an inch, and the 75 spindle E is provided with a sleeve-whirl F, surrounding the tube B with uniform closeness, but out of contact therewith. I arrange 80 the correspondingly reduced bolster-bearing G, within the tube B, so that its upper end, immediately above which would be the center of flexure of the spindle-blade E², will be a considerable distance below the upper end 85 of the tube B, and, substantially so that said center will be equally distant from said upper end of the tube and the lower end of the sleeve-whirl F. Then when, as in doffing, lateral stress is put upon the upper end of the blade, 90 as to the left in Fig. 1, the upper end of the tube B, on the right, and the part of the tube B on the left opposite the lower end of the whirl F, will instantly and simultaneously bear against the corresponding parts of the 95 sleeve-whirl and act as bearings to support the spindle-blade against flexure. With this construction of mounting, I have been enabled 100 to use the spindle-blade of one-eighth inch di-

ameter, and run the same continuously at the hitherto unattainable speed of twenty-three thousand turns a minute, and it has shown no trace of flexure in spite of constant doffing, whereas a spindle of the usual size, when run at the same speed, is bound in its bearing in a few minutes, and a spindle of the same reduced size, but with the common mounting, became soon permanently flexed and unfit for use, for the reasons hereinbefore assumed.

I claim as my invention—

The combination of the tube containing and rigidly combining the bolster and step-bearings, the spindle having close-contact mounting in said combined bearings, so that its "center of flexure" is a short distance

above the upper end of said bolster bearing, and the spindle-whirl extending above and below said "center of flexure," the said bearing tube being provided with normally inert 20 bearings both above and below and equally distant from said "center of flexure," and normally out of contact with the spindle-whirl, but to bear simultaneously against the said whirl and support the spindle when the 25 latter is subjected to lateral stress, substantially as described.

HENRY D. KLOTS.
